UNITED STATES PATENT OFFICE.

PHILIP MUELLER, OF DECATUR, ILLINOIS, ASSIGNOR TO ADOLPH MUELLER, TRUSTEE,
OF DECATUR, ILLINOIS.

FLUSH VALVE FOR TANKS.

Application filed November 12, 1919. Serial No. 337,485.

To all whom it may concern:

Be it known that I, PHILIP MUELLER, a citizen of the United States, residing at Decatur, in the county of Macon and State of Illinois, have invented new and useful Improvements in Flush Valves for Tanks, of which the following is a specification.

This invention relates to valves for flush tanks, and has for its object to provide a tank 10 valve of compact construction; in which efficient and rapid flushing will be secured; which will give a noiseless and complete refill brought about after flushing; from which sediment or foreign matter may be readily 15 removed and which is adapted for either high or low pressure service.

In order that the invention may be clear to those skilled in the art, I have illustrated, in the drawings herewith, embodiments of 20 my invention, which embodiments, may, however, be varied from the mechanical adaptations shown without departing from the invention, the disclosure being illustrative, merely, and not restrictive.

25 In said drawings:

Fig. 1 is a view in side elevation, certain parts being in section for clearness of illustration, of a valve constructed in accordance with my invention.

30 Fig. 2 is a top plan, partly in section, of the valve shown in Fig. 1.

Fig. 3 shows a slightly different arrangement of the valve parts.

Fig. 4 is a sectional view of the form of 35 valve shown in Fig. 3.

Having reference to the drawings by numbers, like numbers designating like parts in the several views, 10 indicates the inlet stub, provided, as is customary, with nuts 11 and 40 12 for securing it to the usual receptacle or tank (not shown) and to the supply pipe (not shown).

The stub 10, in the form of the invention shown in Figs. 1 and 2, is connected by an 45 elbow-passage 13 with the casing of the outlet valve 14, which, in turn, is controlled by the float lever 15, to which any suitable float (not shown) may be attached.

The stub 10 has a through passage, as 50 shown, said passage being straight and of different diameters. In the small section bore of the stub, as shown in Figs. 1 and 2, is located the flow-impeding member or silencer, comprising the central rod 17 having the spiral rib 18, which engages fric-

tionally the wall of the passage, so that when the flow-impeding member or silencer is in place a tortuous passage is provided, which effectively impedes and silences the inrush of water and gives a noiseless refill. 60

It will be observed that the silencer may be readily inserted and withdrawn from the stub, by simply removing the cap-nut 16 which firmly clamps the washer 16' to which the rod 17 is secured, and then, by a suitable 65 tool, engaging the edge of the washer 16', the silencer may be withdrawn. When inserting the silencer 18 the washer 16' limits its downward movement.

The advantage of this construction is, that 70 the valve is adapted to either high or low pressure service. If the pressure is low, the silencer may be initially omitted, or at any time removed, without disturbing the fitting, by simply removing the cap-nut 16, and any 75 clogging of the valve by reason of sediment or foreign matters collecting therein, may be readily taken care of. If the pressure be high, the silencer may be initially installed or at any time supplied to the fitting without the necessity of changing the equipment or taking it down for re-assembling to conform to and meet the needs of high pressure. 80

In that form of the invention shown in 85 Figs. 3 and 4, I have disposed the silencer in a slightly different manner, having arranged it in the cross-passage 19, leading from the inlet stub to the outlet valve casing, the cross-passage 19 being somewhat elongated and closed at its outer end by a nut 20, which 90 may be readily removed without disturbing the rest of the fitting, so as to permit the silencer to be withdrawn or inserted, as may be desired.

The stub 10 has, in both forms disclosed, 95 the chambered section 21 fitted to its top with a water-tight joint and held securely by the cap-nut 16, as shown in Figures 1 and 2 and by the clamping nut 24, as shown in Figures 3 and 4, and additionally in the 100 form shown in Figs. 3 and 4 there is provided a regulation and stop valve 22 which passes thru a suitable stuffing box 23, a wing clamping nut 24 serving to maintain the parts in position. 105

In float valves of this type it is customary to provide bumpers and the like on the float or float lever to limit the downward movement of the float so as to prevent its striking the bottom of the tank and being dented 110

and damaged; and, furthermore, where the float does not fall to the bottom, to relieve the valve of the strain and jamming action incident to sustaining the weight of the float 5 and float lever, I accomplish these results without the necessity of cumbering the equipment with bumpers, by putting a stop 10 on the casing in position to be engaged by the toe 24 projecting from the float lever 15 so as to limit the fall of the opposite end of the float lever and the float (not shown) carried thereby, and prevents bumping of the float.

The float lever 15 is angularly adjustable 15 on the serrated end 26 of this valve stem 27, and is locked thereon by set screw 28, so that it may be adjusted to give the requisite travel of the valve stem to ensure proper opening and closing of the valve. By this 20 arrangement of adjustable float lever and lever stop, I am enabled to initially install the valve so as to get a proper opening and an accurate seating of the valve, and to conveniently compensate for valve wear after 25 use, without the necessity of bumpers or stops on the float or float levers.

The construction is such that both installation or change, for high and low pressures, is readily accomplished, and while I 30 am aware that silencers have been used in equipments of this general type, they have, as known to me, been so arranged that they were not readily accessible for removing or inserting them for different pressures or 35 for cleaning.

Structural changes, such as mechanical skill and expediency would suggest, may, of course, be made, without departing from the spirit of my invention, and I do not limit 40 myself, therefore, except in so far as I am limited by the prior art and terms of the appended claims, to the details herein disclosed.

I claim:

1. A valve of the class described, comprising 45 an inlet stub, a valve casing, an open-ended fluid passage connecting said stub and casing, a removable closure for normally closing one of the open ends of said passage, and a flow-impeding member in said passage 50 and removable through the normally closed end thereof without disturbing or taking down the stub and valve parts.

2. A valve of the class described, comprising 55 an inlet stub, a valve casing, a straight unobstructed passage open at its outer end leading from said stub to said casing, a removable closure for the open end of said passage, and a flow-impeding member mounted 60 in said straight passage and removable through the normally closed end thereof without disturbing or taking down the stub and valve parts.

3. A valve of the class described comprising

65 an inlet stub having an open-ended passage, a valve body, a valve chamber in said body communicating with said passage through an elbow extension, a flow impeding member mounted in said passage, and a closure cap secured to one end of said stub 70 to permit removal of said flow impeding member without disturbing the valve parts.

4. A valve of the class described, comprising 75 an inlet stub, a valve casing, a valve member in said casing, a straight unobstructed passage open at its ends and connecting said stub and casing, a flow-impeding member in said passage and removable therefrom without disturbing the valve parts, and a removable closure for one of 80 the open ends of said passage.

5. A valve of the class described, comprising 85 an open-ended inlet stub having a straight unobstructed passage, a flow-impeding member mounted in the passage of said stub, and a removable closure for one of the ends of said stub.

6. A valve of the class described, comprising 90 an open-ended inlet stub having a straight bore made up of two sections of different diameters, a flow-impeding member removably mounted in the bore section of smaller diameter, and a removable closure for one of the ends of said stub.

7. A valve of the class described, comprising 95 an open-ended inlet stub having a straight bore made up of two sections of different diameters, a flow-impeding member removably mounted in the bore section of smaller diameter and having a spiral frictionally engaging the bore section of smaller diameter and an extension for tool engagement, and a removable closure for one of the ends of said stub.

8. A valve of the class described, comprising 100 an inlet stub, a valve body, a valve mounted in said valve body, a straight pipe section between said inlet stub and said valve body to form a fluid passage therebetween, said pipe section having an outer open end, 110 a flow-impeding member mounted in said straight section, and a removable closure for said open end of said pipe section.

9. A valve of the class described, comprising 115 an inlet stub, a valve body, a valve mounted in said body, a straight pipe section connecting said inlet stub and valve body to form a fluid passage therebetween, said passage having an open outer end, a 120 flow-impeding member mounted in said passage, and a removable closure for said open outer end of said pipe section, said closure serving also to secure said valve body upon said inlet stub.

In testimony whereof I have hereunto set my hand.

PHILIP MUELLER.
